UNITED STATES PATENT OFFICE

WARD LEATHERS, OF HAWORTH, NEW JERSEY, ASSIGNOR TO THE QUADREX CORPORATION, A CORPORATION OF CONNECTICUT

VACUUM CLEANER FILTER VALVE

Application filed November 3, 1930. Serial No. 493,068.

The object of my invention is to produce a bagless vacuum-cleaner wherein the dirt-laden air is filtered in a permanent sleeve-type filter and from which the accumulated dirt may be instantly emptied pneumatically.

In order to accomplish this purpose, I have invented a simple means of removing the dirt, consisting of a single plunger rod 10 equipped in the simplest manner with two valves, and by this simple mechanism I have succeeded in re-routing the flow of air through the filter so that in the operating condition the dirt-laden air enters at the top 15 of the filter depositing the dirt in the bottom thereof, while in the exhausting condition the blast of air enters at the bottom of the filter blowing the dirt from the top thereof and out through the hollow handle 20 or from any other desirable outlet.

In order to set forth my invention in clearly understandable terms, I have prepared the following specification and appended thereto, for purposes of clarity, 25 drawings of which—

Figure I is a partial section of the upper end of the filter and valve mechanism, approximately half size.

Figure II is a section of the lower end of 30 the filter and valve mechanism, approximately half size.

Figure III shows the valves in detail, approximately full size.

Figure IV shows the application of my 35 valved sleeve filter to a type of cleaner where the motor is carried on the handle, approximately full size.

In Figures I and II, 1 is a hollow handle of suitable material, preferably of hard 40 fibre. 2 is a hollow tube of thin section, preferably of metal, such as steel or hard aluminum. The tube 2, the filter top 3 and the handle 1 are all shown clamped together by the screw clamp 4, which may, as shown, 45 also carry, or be integral with, the cord hook 5. The bottom end of the tube 2 is clamped, or otherwise attached, to a suitable hollow part 6 permitting the inflow of dirt-laden air from the motor-blower and hinging the 50 handle thereto as shown in my patent ap-

plications Nos. 492,424, filed Oct. 31, 1930, 472,703, filed Aug. 2, 1930, 477,832, filed Aug. 26, 1930. The tube 2 is provided with ports 7 at both ends. These ports are preferably cut through the metal walls of the 55 tube in such manner that there is no metal removed. This can be accomplished by turning the metal of the port areas outward in the form of wings for stiffening purposes. At the top and bottom edges of the ports, 60 the metal may also be carried out to a shoulder in order to keep the tube practically as rigid where it is supplied with ports as elsewhere. By suitable means, the filter sleeve 8 may be joined to the filter top 3 and in 65 a similar manner to the filter bottom 9. 9 may again be clamped to the tube 2 by a clamp 10 which may also carry, or be integral with, the cord hook. Over a hole, cut in the hollow handle 1, may be attached a 70 stamped part 11. 11 has a hole in the top for the passage of the rod 12, a little supporting cup underneath for holding a felt packing and a hand guard 13. The plunger rod 12 has included with it as a unit as 75 assembly before being put into a vacuum-cleaner the following parts: an annular filter ring or valve 14, held between suitable annular stamped parts rigidly attached to the plunger rod 12, a spring stop 15 also rigidly 80 attached to the rod 12, a spring 16, a spacer 17 free on the rod 12, and a cylindrical sleeve-valve 18 rigidly attached to the rod 12 as by a bail 19.

Figure III shows the rod valve mechanism 85 in practically complete detail, approximately actual size. A heavy felt washer 20 clamped between metal washers and to a cone-shaped piece 21 may be joined to the rod at 22 in suitable manner as by spot 90 welding. The bail 19 may be spot welded to the rod and spot welded to the sleeve 18. The sleeve 18 may consist of thin sheet metal with a facing of thin felt and may be split on the edges longitudinally, as shown at 23, 95 in order to provide a slight spring expansion for tighter fitting, if desired.

The operation of the mechanism is as follows: dirt-laden air from the motor-blower is admitted to the lower end of the 100

tube 2, passes outward through the upper valve 7 being stopped by the port closure at 14, the dirt is filtered from the air by the sleeve 8 and accumulates at the bottom thereof. The principle of carrying the air in the direction of gravity while the dirt is being filtered therefrom is a highly important essential to practical operation. When a sufficient amount of dirt has accumulated, the plunger rod is pressed down from the top a fixed distance, namely, until the button 24 reaches its stop. Such measured distance puts the valve 14 below the upper valve slots 7, thus closing the tube 2 tightly therebelow. The same movement of the rod moves the sleeve 18 the same measured distance to a point below the lower slots 7 thereby uncovering said lower port. The air now flows into the filter from the bottom, out of the filter from the top and out through the hollow handle.

In Figure IV, I have shown a modification of the lower valve only, for the purpose of applying my invention, in practical form, to that type of vacuum-cleaner where the motor is carried on the handle and the axis of the motor coincides with the axis of the handle. 25 is a motor-housing. 26 is the blower-housing and 27 a cylindrical piece of sheet metal surrounding said motor-housing with sufficient space between for the upward flow of dirt-laden air from the blower. An annular part 28 shown riveted to 27 provides a socket for the hollow tube 2 which, in this case, may conveniently be made of hard fibre. The part 28 is provided with a ring of ports 29 and is joined to the tube 2 by suitable means, such as a screw clamp 30. The fabric filter 8 may be suitably attached as by a ring 31 joined to 27 by screws. Another spacer 32, (similar to 17 in Figure I), holds the plunger rod 12 in a central position at the bottom. A dish-like part 33 suitably joined to the bottom of the plunger rod 12 as by up-setting or spot welding carries on its face a ring of felt (shown black in the drawings). The center of the parts 32 and 33 is cut away as much as is practical, leaving only spiders for support. The dirt-laden air may now flow freely from the blower upward through the tube 2 and into the top of the filter, as before described as shown in Figure I. When the plunger rod 12 is depressed, the upper valve moves to the second position, as formerly described, and the dish 33 uncovers the ring ports 29. Thus, the operable functions are similar to those of Figures I, II, and III.

Having set forth my invention in terms so that all those familiar with these arts may readily understand, I wish it understood that the principles involved in my invention may be utilized in many and de-

vious forms of design without departing from the spirit of my invention.

I claim:

1. In a vacuum cleaner, a motor-driven blower, a rigid hollow air duct leading therefrom, a filter, upper and lower ports in said air-duct communicating with the filter, and means of opening and closing the upper and lower ports, the upper being open when the lower is closed and vice versa, for purposes of cleaning said filter pneumatically. 70 75

2. In a vacuum cleaner, a motor-driven blower, a rigid hollow air duct leading therefrom, a filter, upper and lower ports in said air-duct communicating with the filter, and means of simultaneously opening and closing the upper and lower ports, the upper being open when the lower is closed and vice versa, for purposes of cleaning 80 85 said filter pneumatically.

3. In a vacuum cleaner, a motor-driven blower, a rigid hollow air duct leading therefrom, a filter, upper and lower ports in said air-duct communicating with the 90 filter, and means of manually and simultaneously opening the upper and lower ports, the upper being open, when the lower is closed and vice versa, for purposes of cleaning said filter pneumatically. 95

4. In a vacuum cleaner, a hollow tubular air duct leading therefrom, a filter surrounding said air duct, a hollow handle leading from the upper end of the air duct, an upper port in said air duct communicating with the top of said filter, a lower port communicating with the bottom of said filter, and means of opening and closing said upper and lower ports, the upper being open when the lower is closed and vice 100 105 versa, for purposes of cleaning said filter pneumatically through the handle.

5. In a vacuum cleaner, a hollow tubular air duct leading therefrom, a filter surrounding said air duct, a hollow handle leading from the upper end of the air duct, an upper port in said air duct communicating with the top of said filter, a lower port communicating with the bottom of said filter, and means of simultaneously opening and closing said upper and lower ports, the upper being open when the lower is closed and vice versa, for purposes of cleaning 110 115 said filter pneumatically through the handle. 120

6. In a vacuum cleaner, a hollow tubular air duct leading therefrom, a filter surrounding said air duct, a hollow handle leading from the upper end of the air duct, an upper port in said air duct communicating with the top of said filter, a lower port communicating with the bottom of said filter, and means of manually and simultaneously opening and closing said upper 125 130

and lower ports, the upper being open when the lower is closed and vice versa, for purposes of cleaning said filter pneumatically through the handle.

5 Signed at New York in the county of New York and State of New York this thirtieth day of October A. D. 1930.
